UNITED STATES PATENT OFFICE.

WILLIAM KREUZER, OF LONG BRANCH, NEW JERSEY.

INNER LINER FOR SHOES.

1,179,112.

Specification of Letters Patent. Patented Apr. 11, 1916.

Application filed August 2, 1915. Serial No. 43,155.

To all whom it may concern:

Be it known that I, WILLIAM KREUZER, a subject of the Emperor of Germany, and a resident of Long Branch, in the county of 5 Monmouth and State of New Jersey, have invented a new and Improved Inner Liner for Shoes, of which the following is a full, clear, and exact description.

This invention relates to liners for wearing apparel and has for an object the provision of an improved liner which incloses the foot and holds the same from contact with the shoe so as to prevent the transmission or absorption of heat from the foot.

Another object in view is to provide a liner arranged with a substantially air-tight body and a bottom having closed air spaces whereby cold and moisture cannot penetrate to the foot.

A still further object in view is to provide a liner in which air spaces are provided and an absorption material is provided for absorbing any moisture and preventing the same from coming in contact with the foot.

In the accompanying drawings: Figure 1 is a perspective view of a liner embodying the invention; Fig. 2 is a transverse sectional view through Fig. 1 on line 2—2, the 30 same being shown on an enlarged scale; Fig. 3 is an inverted fragmentary perspective view of part of the front of the lining members embodying the invention.

In constructing a liner embodying the invention, a complete covering is provided for the foot and an extra thick arrangement is made at the position opposite the bottom of the foot which will absorb moisture and which will space the foot an appreciable 40 distance from the bottom of the shoe. The idea intended is to provide a liner which will prevent the foot from becoming wet or moist and which will present means for maintaining the feet in a warm condition 45 in extremely cold weather. There are, of course, no heating elements in the liner but means are presented which will prevent any considerable radiation of heat from the feet and also which will prevent the transmission 50 of moisture from the shoe to the foot, thus relieving the foot of the cold transmitted with the moisture.

In the accompanying drawing, 1 indicates a paraffined covering member formed of

paper or a composition of rubber, cotton and paper mixed. The cover 1 and also the lining 2 for covering 1 may be made as shown in Fig. 1, with a foot portion 3 and a leg portion 4, but if desired may be made with only the foot portion. The lining member 2 is preferably a good strong quality of tissue paper and the same is substantially air-tight and will thus prevent the air heated by the foot from radiating the heat to any appreciable extent. Arranged to rest on the bottom part of the inner members 1 and 2 is a strip 5 of blotting paper or other water absorbing material which is provided with a plurality of spaced supporting members 6, these members being formed of paper of any desired kind arranged in layers and secured together by an adhesive in any suitable manner so that there will be a large number of substantially closed air spaces 7. This will prevent the paper 5 from coming in direct contact with the lining member 2. On top of the blotting paper 5 is a sheet 8 of oiled paper, celluloid or other similar material formed with a plurality of perforations 9 whereby the foot is 80 kept out of contact with the blotting paper 5. In this way the foot is completely enclosed by substantially air-proof members, as for instance, members 1 and 2, and is supported by a plurality of members which 85 present closed air spaces and present means for taking up any moisture that may eventually find its way through the bottom of the shoe and through the bottom part of the lining members 1 and 2. 90

It is evident that all of the members forming the device are comparatively thin so that an appreciable amount of space in the shoe will not be utilized, so that in wearing this device an old shoe may be used of the proper 95 size or a new shoe slightly larger than that usually worn. Where a person is continually exposed to the cold for an appreciable length of time and also exposed to the snow and other moisture on the ground, a certain amount of this moisture will penetrate the shoe or boot if made of leather and will carry with it a chilling disagreeable effect. In forming the lining as described and by providing the absorbing material, the moisture thus transmitted through an ordinary leather shoe will be absorbed or prevented 100 from contacting with the foot, thus main- 105

taining the foot continually dry so as to allow a normal proper circulation of the blood.

What I claim is:—

5. 1. In a liner of the character described, a pair of lining members adapted to completely inclose the foot, and an extra lining member arranged in the bottom, and formed of moisture absorbing material.
10. 2. In a liner of the character described, a lining member adapted to inclose the foot, an extra lining member arranged in the bottom of the first mentioned lining member, a plurality of spaced supporting members arranged on the bottom of said extra lining member, and a covering for said extra lining member.
15. 3. In a liner for shoes and the like, a pair of lining members adapted to form an inclosing structure for the foot, a strip of blotting paper arranged in the bottom of said lining members, a plurality of spaced strips connected with the bottom of said blotter for spacing the blotter away from said first mentioned lining members and for providing closed air spaces, said blotting paper being adapted to absorb moisture penetrating the shoe, and a substantially

moisture-proof covering member arranged on said blotting paper.

4. In a liner of the character described, a member adapted to inclose the foot, a strip of blotting paper arranged on the bottom of said member, and a perforated substantially waterproof strip of material arranged on top of said blotting paper.

5. In a liner of the character described, a member of tissue paper adapted to inclose the foot, an inclosing member surrounding said tissue paper formed of substantially waterproof material, a strip of blotting paper arranged in the bottom of said tissue paper, means for spacing said blotting paper a short distance above the bottom of said tissue paper and for providing closed air spaces, and a perforated strip of substantially waterproof material arranged on said blotting paper.

In testimony whereof I have signed my name to this specification in the presence of two subscribing witnesses.

WILLIAM KREUZER.
